UNITED STATES PATENT OFFICE

ARVEY SMITH, OF WINCHESTER, ILLINOIS, ASSIGNOR TO KOEHRING COMPANY, OF MILWAUKEE, WISCONSIN, A CORPORATION OF WISCONSIN

DERRICK

Application filed April 30, 1925, Serial No. 27,095. Renewed November 6, 1926.

My invention relates to improvements in derricks and has reference more particularly to those used on road pavers for the purpose of hoisting batch boxes from donkey trains and swinging such boxes to the machines. A well known type of derrick for this purpose, embodies a mast which is mounted for vertical sliding and when free of load, is raised by spring means, so that a swivel foot on its lower end is clear of the ground. Then, when the mast is under load, the foot descends onto the ground and forms a pivotal support for the mast so that the latter may be turned to swing the load to the desired point. It is the primary object of my invention to improve upon this type of derrick, by the provision of co-acting means embodied with the mast and its foot, for automatically effecting turning of the mast when it is under load, and in this connection, a further aim is to provide a foot which is sufficiently heavy to remain stationary upon the ground during at least part of the upward movement of the mast, effected by the spring means. Thus, after the mast has lowered under load and has swung the load to the desired point, freeing of the load and consequent raising of the mast by the spring means, will effect reverse turning of said mast to again position it at load-receiving position.

A still further object is to make novel provision to permit the foot of the mast to adapt itself to the ground, regardless of any irregularities in the latter, without danger of placing any prying strain upon the connecting means between said foot and the mast, so that there is no danger of breaking such connecting means or causing binding thereof.

Yet another object is to provide a unique brake means whereby the turning movement of the mast may be controlled.

With the foregoing in view, the invention resides in the novel subject matter herein-after described and claimed, the description being supplemented by the accompanying drawings.

Figure 1 is a side elevation partly broken away and in section, showing the relation of parts when the derrick is in readiness to start lifting a load.

Figure 2 is a view similar to Fig. 1 but showing the mast and associated parts turned substantially to 180° under the influence of the load.

Figures 3 and 4 are detail horizontal sectional views as indicated by lines 3—3 and 4—4 of Fig. 2.

In the drawings above briefly described, the numeral 1 designates a portion of the common frame of a road paver, said frame having upper and lower bearings 2 and 3 in which a mast 4 is mounted slidably and rotatably. A conventional boom 5 is shown extending from the mast 4, connected at its upper end with the bearing 2, by a chain 6, and provided with sheaves 7 over which a hoisting cable 8 passes. A portion of this cable is shown engaged with a pulley block 9 for connection with a batch box 10 to be lifted, and other portions of said cable are shown strained around sheaves 11 and 12 carried respectively by the mast 4 and the frame 1.

At 13, a coiled tension spring is shown, one end of said spring being appropriately connected with the frame 1, while its other end is connected in the conventional or any desired way with the mast 4, so that the spring exerts its power to raise the mast and associated parts when free of load. As soon as the derrick is connected with a load however, and the cable 8 is operated, the mast 4 slides downwardly against the tension of the spring 13. Heretofore, this downward sliding of the mast has brought a foot at its lower end into contact with the earth, and after lifting of the load, this foot has constituted a pivotal support for the mast so that it may be swung about a vertical axis to move the load to the desired point. This moving is effected manually, by the use of one or more men pulling upon a rope, but due to the nature of my invention, turning of the mast 4 and consequent swinging of the load to its destination is automatically carried out. This result may be obtained in numerous ways, one of which is illustrated, and described below.

At 14, a heavy metal foot is shown for the mast 4, said foot having a recess or bore 15 whose opposite sides are provided with helical

cam grooves or tracks 16. These grooves or tracks are engaged by a pair of rollers 17 on the ends of a horizontal member 18 which is disposed in the recess 15, the use of rollers being preferable, although other shoes could well be employed if desired. The member 18 is connected by a flexible joint with the lower end of the mast 4, so that the foot 14 may adapt itself to irregularities on the surface of the ground. In the present showing, the flexible joint comprises an ear 19 rising from the member 18 and receiving in a notch 20 in the lower end of the mast 4, a pivot pin 21 being passed horizontally through said mast and ear. This pin, I have shown transverse to the axis of the rollers 17 to allow pivotal movement in one direction, and it will be seen that said rollers will allow pivotal movement in a direction at right angles, so that in effect a universal connection is provided between the mast and the foot 14.

Preferably, the tracks or grooves 16 extend entirely to the top of the foot 14 and withdrawal of the rollers or the like 17 from engagement with said tracks, is prevented by a cap ring or the like 22 which may well be secured to the top of the foot by screws 23.

Above the bearing 3, I have shown a vertically elongated, flat-sided, sectional body 24 secured to the mast 4 by fasteners 25. This body 24 passes slidably through an opening in a brake drum 26, establishing a driving connection between said drum and the mast 4. A stationary brake band 27 surrounds the drum 26 and may well be confined between flanges 28 on said drum, so that the latter is held against vertical movement. The band 27 may be stationarily held by any preferred means such as the bracket arm 29, and appropriate operating connections 30 may be provided for the brake band 27, said connections preferably having a foot lever 31 by means of which they may be operated to contract the band 27.

Ordinarily, the parts may be considered as standing substantially as shown in Fig. 1, except that the foot 14 and the mast 4 will be elevated to a slightly greater extent, by the spring 13, so that said foot is clear of the ground. When now, the derrick is connected to a load and the cable 8 is wound in the usual manner, the first movement which takes place, is downward sliding of the mast 4 through the brake drum 26, until the foot 14 rests upon and adapts itself to the ground. During this movement, the brake 27 has been held in contracted position and the operator will continue to hold it in this condition until the derrick operates to raise the load 10 to the desired point. Thus, during this raising movement, the mast 4 is held against rotation. When the load has been raised to the desired extent however, the brake is totally or partially released, with the result that the load 10 slides the mast 4 downwardly with respect

to the foot 14 which then rests stationarily on the ground. This causes the rollers or the like 17 and the tracks 16, to effect rotation of the mast 4, so that the load may be swung horizontally to any desired point, within an arc of substantially 180°. As soon as the load is dumped, the spring 13 exerts its force to raise the mast 4, but the foot 14 is sufficiently heavy to then remain stationarily upon the ground, with the result that the co-acting tracks and shoes 16—17, act reversely from their previous action and thus swing the mast 4 and associated parts to their original positions. By the time this relation takes place, the shoes 17 have reached the upper extremities of the tracks 16 and the mast 4 will then serve to elevate the foot 14 to a point above the surface of the ground under the influence of the spring 13.

It will be seen from the foregoing that I have provided distinct and very advantageous improvements in derricks of the type embodying a mast which is normally raised but is shifted downwardly under load. On account of the excellent results obtainable from the details disclosed, they may of course be followed, but it is to be understood that the present disclosure is for illustrative purposes only and that within the scope of the invention as claimed, numerous modifications may be made.

When there is no load on the mast, it is held in its highest position by the coil spring. When the mast is thus held, the foot is off the ground, and due to its weight, it is at its lowest position on the mast as shown in Figure 1. The brake is now applied, and a load hoisted. The weight of the load causes the mast to move downwardly until the foot is pressed against the ground. The brake prevents turning of the mast, so that any further downward movement of the same must be accompanied by a turning of the foot, due to the helical cam tracks therein, and the shoes carried by the mast. Turning of the foot is prohibited by its frictional and compressive engagement with the ground caused by its own weight and the weight of the load on the mast. When the brake is released, the mast is free to turn in the foot, and does so under the weight of the load carried thereby.

I claim:

1. In a derrick of the type having a mast mounted for downward movement under load, and provided also with means for raising said mast when free of load; a ground-engaging foot for the mast adapted to rest stationarily on the ground during downward movement of the mast, and co-acting means embodied with the foot and mast for turning said mast with respect to said foot upon said downward movement of the mast.

2. A machine as specified in claim 1; said co-acting means comprising a helical cam track and a shoe engaging the same.

3. In a derrick of the type having a mast mounted for downward movement under load, and provided also with means for raising said mast when free of load; a ground-engaging foot for the mast adapted to rest stationarily on the ground during downward movement of the mast, said foot having a recess receiving the lower end of the mast, the wall of said recess being formed with a helical cam track, and a lateral shoe on said lower end of the mast engaging said cam track and disposed at the upper end thereof when the mast is free of load.
4. A structure as specified in claim 1; said foot being sufficiently heavy to remain stationary on the ground and cause reverse turning of the mast under the influence of said co-acting means during at least part of the upward movement of said mast.
5. A structure as specified in claim 3; said foot being sufficiently heavy to remain stationary on the ground and cause reverse turning of the mast under the influence of said cam track and shoe during at least part of the upward movement of said mast.
6. A structure as specified in claim 1; said mast being jointed adjacent said co-acting means to permit said foot to adapt itself to the surface of the ground without danger of placing a prying strain on said co-acting means.
7. In a derrick of the type having a mast mounted for downward movement under load, and provided also with means for raising said mast when free of load; a ground-engaging foot for the mast adapted to rest stationarily on the ground during downward movement of the mast, said foot having a recess receiving the lower end of the mast, the wall of said recess being formed with opposed helical cam tracks, a member movable vertically in said recess and having shoes projecting in opposite directions and engaging said tracks, and a flexible joint connecting said member with the lower end of the mast, to permit the aforesaid foot to adapt itself to the surface of the ground without danger of placing prying strain on the aforesaid member.
8. A structure as specified in claim 1; together with a brake drum surrounding said mast and having a driving connection therewith, said driving connection permitting sliding of the mast through the drum, and a brake co-operable with said drum, provision being made for holding said drum against vertical movement.
9. In a derrick of the type having a mast mounted for downward movement under load, and provided also with means for raising said mast when free of load; a brake drum surrounding said mast and having a driving connection therewith, said driving connection permitting sliding of the mast through the drum, and a brake co-operable with said drum, provision being made for holding said drum against vertical movement.
10. In a derrick of the type having a mast mounted for downward movement under load, and provided also with means for swinging the mast to transfer the load from one place to another cooperative with the ground on said downward movement of the mast, a brake drum associated with the derrick mast for controlling the swinging and movement of the same and brake means co-operating with said drum substantially as set forth.
11. In a derrick of the type having a mast mounted for downward movement under load, means associated with the derrick for automatically swinging the same incident to its vertical movement, brake drum means connected with the mast for controlling its swinging movement and including a brake band acting on the brake drum substantially as described.
- In testimony whereof I have hereunto affixed my signature.
- ARVEY SMITH.
